UNITED STATES PATENT OFFICE.

FRANK C. WATKINS, OF PHILADELPHIA, PENNSYLVANIA, ASSIGNOR, BY MESNE ASSIGNMENTS, TO THE UNITED STATES KROTOPHONE COMPANY, OF NEW YORK, N. Y.

TELEPHONE.

SPECIFICATION forming part of Letters Patent No. 369,376, dated September 6, 1887.

Application filed November 15, 1886. Serial No. 218,956. (No model.)

To all whom it may concern:

Be it known that I, FRANK C. WATKINS, a citizen of the United States, residing at Philadelphia, in the county of Philadelphia and 5 State of Pennsylvania, have invented certain new and useful Improvements in Krotophones; and I do declare the following to be a full, clear, and exact description of the invention, such as will enable others skilled in the art to which 10 it appertains to make and use the same, reference being had to the accompanying drawing, and to the letters and figures of reference marked thereon, which forms a part of this specification.

15 My invention has relation to certain new and useful improvements in the construction of krotophone receiving-instruments, and the object is to provide a simple, reliable, and convenient form of receiver, whereby the voice 20 will be reproduced as received from the transmitter, thus avoiding all tendency to interruption from foreign influences, such as induced currents and other causes common to that class of receiving-instruments using a magnet or 25 coil; and to these ends the novelty consists in the peculiar construction and arrangement of the parts of the same, as will hereinafter be more fully described, and particularly pointed out in the claim.

30 The figure in the drawing is a longitudinal section of my improved krotophone-receiver.

The present invention is designed as an improvement in form upon the patent granted July 6, 1886, to Edward S. Spaulding, No. 345,084.

35 A is the receiver, and is provided with the usual ear-piece, B, which is secured to the receiver in any suitable manner.

C is a diaphragm having an integral circu- 40 lar concave recess, e, in its center, and D is a second diaphragm, mounted a short distance in front of and parallel with the first one, C,

being separated therefrom by a flexible washer, E.

The diaphragm C is preferably stamped up 45 from a piece of sheet-iron or other suitable conducting material, while the other diaphragm, D, is made of any suitable non-conducting but sonorous material, as a membrane or any of the woods.

50 The inner face of the diaphragm D is provided with a small carbon wafer, d, corresponding to the size of the recess e, so that when the instrument is held horizontal, as is its position while in use, the contact ball e 55 will by gravity complete the circuit between the diaphragm C and the wafer d. Of course, when the instrument is held or placed at rest in a vertical position, the carbon ball e falls into the recess in diaphragm C, and breaks 60 the contact. The wafer d is in electrical connection with binding-post a and the diaphragm C, connected to the post b. Through the medium of the flexible washer E the two diaphragms may be adjusted with reference to 65 each other by tightening or loosening the ear-piece B.

I do not broadly claim a contact between a diaphragm and a back support.

70 For a complete description of the operation of the instrument, reference may be had to the patent to Spaulding, krotophone, granted July 6, 1886, No. 345,084.

Having thus described my invention, what I claim is—

75 The combination, with the diaphragm C, provided with recess e, of the wafer d and carbon ball e, as set forth.

In testimony whereof I affix my signature in presence of two witnesses.

FRANK C. WATKINS.
